(57) **CLAIM**

The ornamental design for a plug-type power inverter, as shown and described.

DESCRIPTION

FIG. 1 is a perspective view of a plug-type power inverter showing our new design;

FIG. 2 is a top view of the plug-type power inverter thereof;

FIG. 3 is a right-hand side view of the plug-type power inverter thereof;

FIG. 4 is a bottom view of the plug-type power inverter thereof;

FIG. 5 is a left-hand side view of the plug-type power inverter thereof;

FIG. 6 is a front view of the plug-type power inverter thereof;

FIG. 7 is a rear view of the plug-type power inverter thereof;

FIG. 8 is a perspective view of a second embodiment of the design shown in FIG. 1;

FIG. 9 is a top view of the variant of the design shown in FIG. 1;

FIG. 10 is a right-hand side view thereof;

FIG. 11 is a bottom view thereof;

FIG. 12 is a left-hand side view thereof;

FIG. 13 is a front view thereof; and,

FIG. 14 is a rear view thereof.
